UNITED STATES PATENT OFFICE.

ALFRED C. FULLER, OF HARTFORD, CONNECTICUT.

DESIGN FOR A TOOTH-BRUSH.

49,085.

Specification for Design. Patented May 23, 1916.

Application filed February 7, 1916. Serial No. 76,875. Term of patent 14 years.

To all whom it may concern:

Be it known that I, ALFRED C. FULLER, a subject of the King of Great Britain, residing at Hartford, in the county of Hartford and State of Connecticut, have invented a new, original, and ornamental Design for Tooth-Brushes, of which the following is a specification, reference being had to the accompanying drawings, forming part thereof, in which the figure is a perspective view

of a tooth-brush showing my new and improved design.

I claim—

The ornamental design for a tooth brush, as shown.

ALFRED C. FULLER.

Witnesses:

E. F. EATON,
LOUIS V. LUCIA.
